UNITED STATES PATENT OFFICE.

ROY C. J. WELCH AND STANLEY L. SWEENEY, OF PORT COQUITLAM, BRITISH COLUMBIA, CANADA.

CONVERTIBLE ACETYLENE-GAS AND OIL LANTERN.

1,208,059.

Specification of Letters Patent. Patented Dec. 12, 1916.

Application filed January 11, 1916. Serial No. 71,569.

To all whom it may concern:

Be it known that we, ROY C. J. WELCH and STANLEY L. SWEENEY, both citizens of the Dominion of Canada, residing at Port Coquitlam, in the Province of British Columbia, Canada, have invented certain new and useful Improvements in Convertible Acetylene-Gas and Oil Lanterns, for which the following is a specification.

- 10 This invention relates to a portable lantern of that class used by railway brakemen and yardmen and is particularly designed to enable either acetylene gas or oil to be used as the illuminant, the lamp being provided with 15 a supplementary oil reservoir and wick burner which are respectively used in conjunction and are interchangeable with the carbide holder and water reservoir of an acetylene gas lamp.
- 20 Although particularly designed for a lantern of the class above described, the arrangement of parts is equally applicable with slight modification to any lantern.

The invention is fully described in the following specification, reference being made to the drawings by which it is accompanied, in which:

Figure 1 is a vertical section through the lantern as adapted to use acetylene gas. Fig. 2 is a similar view showing the application of the interchangeable wick burner and its removable oil reservoir fitting the carbide holder, and Fig. 3 is a sectional plan on the line *a—a* in Fig. 1. Fig. 4 is a cross section 35 of the carbide holder.

In these drawings 2 represents a gas chamber to which is secured the wire guard and frame 3 which supports the hood 4 of the lamp, between which hood and a gallery 5, secured on the upper side of the chamber, the glass globe 6 is removably inserted. The wire frame 3 may be carried down to form a base for the lamp or an annular base may be secured to the lower part of the chamber 45 to project beneath its bottom.

The top of the gas chamber 2 is concentrically apertured and threaded to receive a correspondingly threaded connection 8 secured to the bottom of a water reservoir 9, or 50 interchangeable with this water reservoir the threaded end of a wick oil burner 10. In the bottom of the chamber 2 is a concentric aperture to the edge of which is secured a screw threaded ring 11 adapted to receive a 55 corresponding thread on the bottom of a car-

bid cage 12. This cage 12 within the gas chamber 2 is of wire mesh or is finely perforated and is furnished with the customary central tube 13 secured on a base plate 14 through which tube the water by which the carbide is converted into gas is delivered to the underside of the base plate and therefore beneath the carbide in the cage. A retaining plate 15 having a spring secured on its upper side may be furnished, which plate fits 65 loosely on the central tube 13 to prevent the carbide shaking loose and the carbide cage has a gauze mesh cover 16 through which the tube 13 projects or is accessible.

Water is delivered from the reservoir 9 70 into the tube 13 of the carbide chamber by a tube 17 admission of the water to this tube being controlled within the reservoir by a valve 18, the stem of which is threaded through a nut 19 secured in the top of the 75 reservoir 9 and provided with a finger engagement thereabove. In the top of the reservoir is a closable filling aperture 20.

A tube 21 is axially secured in the top 80 and bottom of the water reservoir 9, in the upper end of which tube is socketed the gas burner 22 and in this tube beneath the burner any suitable gas filtering material may be packed. The gas generated may thus pass direct from the chamber 2 to the burner 22 85 and as the carbide is disintegrated it will pass through the mesh of the cage 12 into the chamber 2. The carbide cage 12 may be withdrawn from below for cleaning and charging with carbide.

If it is required to use oil instead of acetylene gas for the illuminant, the water reservoir with its connected burner, etc., is removed from the gas chamber 2 and the wick oil burner 10 is substituted. The carbide cage 12 is removed from below and being emptied of its ash and oil reservoir 25, which is adapted to closely fit the carbide chamber, is inserted within it. The upper end of this oil reservoir has a concentric aperture the edge of which is upwardly flanged to fit within the screw connection of the oil wick burner 10 and to retain a gasket of leather or the like in the joint between them to make an effective joint.

The convertible gas and oil lantern hereinbefore described is free from the objections commonly urged against lamps of this character. Its weight need not exceed that of an ordinary oil lamp while the light of the 110

acetylene is more brilliant and distinct and is preferred by those who use the lamp, while if for any reason oil is required to be used, the reservoir 25 can be quickly introduced 5 and the oil burner 10 is readily substituted for the water reservoir and its gas burner.

As an acetylene lantern, the arrangement 10 as above described has the further advantage that the water reservoir is in direct communication with the carbide container and being adjacent the heat of the burner, is not exposed to the risk of the water service freezing as is commonly the case where the water reservoir is at the top of the lamp and connected to the carbide chamber by a flexible 15 tube.

Having now particularly described our invention, we hereby declare that what we claim as new and desire to be protected in by 20 Letters Patent, is:

1. In a lantern of the class described, the combination with a chamber having an aperture in the top and bottom, a carbide holder secured in and forming a closure for 25 the lower aperture and projecting into the chamber, a water reservoir removably connected in the upper aperture of the chamber, said reservoir having a controllable water delivery into the carbide holder, and a 30 tube through the water reservoir communicating with the chamber, and a gas burner inserted in the upper end of this tube, said reservoir, said controllable water delivery and said tube being bodily removable as a 35 unit from said chamber.

2. In a lantern of the class described, the combination with a chamber having an aperture in the top and bottom, a carbide holder having apertured sides secured in 40 and forming a closure for the lower aperture and projecting into the chamber, a water reservoir removably connected in the upper aperture of the chamber, said reservoir having a controllable water delivery into 45 the carbide holder, and a tube through it communicating with the chamber, and a gas burner inserted in the upper end of the tube, said reservoir, said controllable water delivery and said tube being bodily removable 50 as a unit from said chamber.

3. In a lantern of the class described, the combination with a chamber having an aperture in the top and bottom, a carbide holder secured in and forming a closure for 55 the lower aperture of the chamber to project into it and having apertured side walls, a central tube having a perforated disk secured on its lower end which disk loosely fits the carbide holder, a water reservoir removably connected in the upper aperture of the chamber, said reservoir having a controllable water delivery into the central tube of the carbide holder, and a tube through 60 the water reservoir the lower end of which 65 communicates with the chamber, and a gas

burner secured in the upper end of the tube, said reservoir, said controllable water delivery and said tube being bodily removable as a unit from said chamber.

4. In a lantern of the class described, the combination with a chamber having an aperture in the top and bottom, a carbide holder secured in the lower aperture and projecting into the chamber, a water reservoir removably secured in the upper aperture of the chamber, said reservoir having a controllable water delivery into the carbide holder, and a tube through the reservoir communicating at its lower end with the chamber, a gas burner removably inserted in the upper end of the tube, an oil reservoir adapted to fit the carbide holder in the upper end of which reservoir is an aperture adjacent the upper aperture of the chamber, and a wick burner adapted to be secured in the upper aperture of the chamber and interchangeable with the water reservoir, the under end of which burner is adapted to seat upon and form a joint around the aperture in the upper end of the oil reservoir. 80

5. In a lantern of the class described, the combination with a chamber having an aperture in the top and bottom, a carbide holder secured in the lower aperture to project into the chamber, said holder having apertured side walls, a central tube secured at its lower end in an apertured disk adapted to loosely fit the carbide holder, a water reservoir removably secured in the upper aperture of the chamber, said reservoir having a controllable water delivery into the central tube of the carbide holder, and a tube through the reservoir communicating at its lower end with the chamber, a gas burner removably inserted in the upper end of said tube, an oil reservoir adapted to fit the carbide holder when the central tube and disk are removed, in the upper end of which oil reservoir is an aperture concentric with and adjacent the upper aperture of the chamber, and a wick burner adapted to fit the upper aperture of the chamber and removably interchangeable with the water reservoir, the lower end of which burner is adapted to seat within the chamber around the aperture in the upper end of the oil reservoir. 100

6. In a lantern of the class described, the combination with a chamber having a concentric aperture in the top and bottom, a carbide holder secured in the lower aperture of the chamber to project within it and having apertured side walls and an apertured removable cover, a central tube secured at its lower end in an apertured disk adapted to loosely fit the carbide holder, a water reservoir removably secured in the upper aperture of the chamber, said reservoir having a controllable water delivery 110 115 120 125 130

into the central tube of the carbide holder, and a tube through the reservoir communicating at its lower end with the chamber, a gas burner removably inserted in the upper end of said tube, an oil reservoir adapted to fit the carbide holder when the cover and the central tube and disk are removed, in the upper end of which oil reservoir is an aperture concentric with and adjacent to the upper aperture of the chamber, and a wick oil burner adapted to fit the upper aperture of the chamber and removably interchangeable with the water reservoir, the lower end of which burner is adapted to seat within the chamber around the aperture in the upper end of the oil reservoir. 15
In testimony whereof we affix our signatures.

ROY C. J. WELCH.
